F. W. BILLIG

VACUUM FEED TANK

Filed Jan. 3, 1925

UNITED STATES PATENT OFFICE.

FRED W. BILLIG, OF JACKSON, MICHIGAN.

VACUUM FEED TANK.

Application filed January 3, 1925. Serial No. 367.

This invention relates to improvements in vacuum feed tanks.

The main objects of this invention are:

First, to provide an improved vacuum feed tank which is very positive in its action and is not likely to become inoperative in use.

Second, to provide in a vacuum feed tank an improved valve mechanism.

10 Third, to provide in a vacuum feed tank an improved discharge valve mechanism for the float chamber.

Objects pertaining to details and economies of construction and operation of my 15 improved vacuum feed tank will definitely appear from the detailed description to follow.

I accomplish the objects of my invention by the devices and means described in the 20 following specification. The invention is clearly defined and pointed out in the claims.

A structure embodying the features of my invention is clearly illustrated in the accompanying drawing forming a part of this 25 application, in which:

Fig. I is a vertical section on a line corresponding to line 1—1 of Fig. VI.

Fig. II is a plan view.

30 Fig. III is a fragmentary view partially in section on broken line 3—3 of Fig. I.

Fig. IV is a detail section on a line corresponding to line 4—4 of Fig. II.

Fig. V is an enlarged detail section on a line corresponding to broken line 5—5 of 35 Fig. II.

Fig. VI is a detail section on a line corresponding to line 6—6 of Fig. I.

In the drawing the sectional views are taken looking in the direction of the little 40 arrows at the ends of the section lines and similar numerals of reference indicate similar parts throughout the several views.

45 Referring to the drawing, I provide a cylindrical tank 1 having a horizontal partition 2 therein providing a float chamber 3 and a discharge chamber 4. The discharge chamber is connected to the carburetor or the like by the pipe 5. The fuel or supply connection for the float chamber is indicated at 6.

The suction connection 7 is connected to the float chamber through the suction passage 8, a portion of this passage being vertical as shown in Fig. V and having a valve 55 seat 9 at its lower end. Within the cham-

ber I mount a cylinder 10 provided with a plunger 11. This cylinder is connected to the suction passage by the passage 12, the passage 12 being controlled by the ball valve 13 disposed at the upper end of the vertical portion 9 of the suction passage.

The suction passage 8 is controlled by the valve 14 which has a tappet 15 coacting with the valve 13 to lift the valve 13 from its seat when the suction valve 14 is closed thereby opening the cylinder to the suction and consequently actuating the plunger.

The discharge passage from the float chamber to the discharge chamber comprises the valve casing 16 having a pair of ports 17 and the disk valve 18 having ports therein adapted to be brought into register with these ports 17. The valve 16 is supported in the valve casing for rotary and limited vertical movement as is indicated in Fig. I 75 so that there is no likelihood of its binding or becoming wedged, the weight of the liquid in the float chamber tending to hold it to its seat.

The valve 18 is provided with a stem 19 which engages a socket in the coupling member 20 on the valve and projects through the top of the casing permitting limited longitudinal movement between the valve and the stem. On the upper end of the stem is an arm 21 which is connected by the link 22 to the plunger 11 so that when the plunger is actuated the valve is rotated to open the same.

The spring 23 connected to the link 22 and to a pin 24 depending from the head or cover 25 of the float chamber serves to return the valve to closed position and the plunger to its initial position.

The float is provided with a yoke 26 which is pivotally connected to a spring 27, the ends of the spring being mounted at 28 on the depending bosses 29 on the cover. This spring has a lost motion connection to the valve 14, the valve having a stem 30 arranged through the spring and provided with the tappet shoulder 31 on the collar 32.

The float chamber is provided with a vent port 33 controlled by the downwardly seating valve 34 having a stem 35 arranged through this spring member 27 and having spaced tappets 36 at either side of the spring, thereby providing lost motion connection for the vent valve to the spring member.

With this arrangement, when the float 110

rises it lifts the spring 27 and when the spring passes a predetermined point it acts with a snap action to close the suction valve 14 and open the cylinder valve 13, also to 5 open the vent valve 34. The opening of the valve 13 actuates the plunger thereby opening the discharge valve and the vent valve 34 being also opened permits the contents of the fluid chamber to discharge. As 10 soon as the float lowers beyond a predetermined point the spring member 27 is again actuated to open the suction valve 14 and close the valve 13, and to close the vent valve so that the float chamber is again subject 15 to the vacuum. The discharge chamber is provided with the usual vent tube 37.

With the parts thus arranged I provide a structure in which the action is very positive. The discharge valve is easily operated and is not likely to become clogged. 20 At the same time it is not likely to leak as the movement thereof tends to free the valve of any sediment and the weight of fluid tends to seal the valve.

25 I have illustrated and described my invention in an embodiment which I have found very satisfactory. I have not attempted to illustrate or describe other embodiments or adaptations which I contemplate as I believe the disclosure here made will enable the embodiment or adaptation of my invention as may be desired.

Having thus described my invention what I claim as new and desire to secure by Letters Patent is:

1. In a device of the class described, the combination of a float chamber provided with a supply connection, a float, a cylinder provided with a plunger, there being 40 a suction passage opening to said float chamber and a cylinder passage connecting said cylinder to said suction passage, a discharge valve for said float chamber, a stem for said discharge valve having an arm at its upper end, a valve for said cylinder passage, a suction valve for said float chamber suction passage having a tappet acting to open said cylinder valve when the suction valve is closed, a vent valve for said float chamber, operating connections for said float to said vent and suction valves including a bowed spring element connected to said float and mounted at its ends and having lost motion connections to said suction and 45 vent valves whereby when the spring member is raised by the float beyond a predetermined point it acts with snap action, a link connecting said discharge valve stem arm to said plunger, and a return spring 50 connected to said link and acting to hold said discharge valve normally closed.

2. In a device of the class described, the combination of a float chamber provided with a supply connection, a float, a cylinder provided with a plunger, there being 55

a suction passage opening to said float chamber and a cylinder passage connecting said cylinder to said suction passage, a discharge valve for said float chamber, a stem for said discharge valve having an arm at its upper end, a cylinder valve for said cylinder passage, a suction valve for said float chamber suction passage having a tappet acting to open said cylinder valve when the suction valve is closed, a vent valve for said float chamber, operating connections for said float to said vent and suction valves, a link connecting said discharge valve stem arm to said plunger, and a return spring connected to said link and acting to hold said discharge valve normally closed.

3. In a device of the class described, the combination of a float chamber provided with a supply connection, a float, a cylinder provided with a plunger, there being a suction passage opening to said float chamber and a cylinder passage connecting said cylinder to said suction passage, a discharge valve for said float chamber comprising a valve casing and a horizontally disposed 90 rotary disk valve mounted in said casing for limited vertical movement, a stem for said discharge valve having an arm at its upper end, a cylinder valve for said cylinder passage, a suction valve for said float chamber 95 suction passage having a tappet acting to open said cylinder valve when the suction valve is closed, a vent valve for said float chamber, a link connecting said discharge valve stem arm to said plunger, and a return spring connected to said link and acting to hold said discharge valve normally closed.

4. In a device of the class described, the combination of a float chamber provided with a feed connection, a float, a cylinder provided with a plunger, there being suction passages for said float chamber and cylinder, a rotary discharge valve for said float chamber, a cylinder valve for said cylinder passage, a suction valve for said float chamber suction passage operatively associated with said cylinder valve to open it when the suction valve is closed, a vent valve for said float chamber, operating connections for said float to said vent and suction valves including a spring element operatively connected to said float and having lost motion connections to said suction and vent valves whereby when the spring element is actuated by the float beyond a predetermined point it acts with a snap action, operating connections for said plunger to said discharge valve, and a spring 110 acting to hold said discharge valve normally closed.

5. In a device of the class described, the combination of a float chamber provided with a feed connection, a float, a cylinder provided with a plunger, there being suc- 130

- tion passages for said float chamber and cylinder, a rotary discharge valve for said float chamber, a cylinder valve for said cylinder passage, a suction valve for said float chamber 5 suction passage operatively associated with said cylinder valve to open it when the suction valve is closed, a vent valve for said float chamber, operating connections for said float to said vent and suction valves, 10 operating connections for said plunger to said discharge valve, and a spring acting to hold said discharge valve normally closed.
6. In a device of the class described, the combination of a float chamber provided 15 with a feed connection, a float, a cylinder provided with a plunger, there being suction passages for said float chamber and cylinder, a discharge valve for said float chamber comprising a valve casing and a 20 horizontally disposed rotary disk valve mounted in said casing for limited vertical movement, a cylinder valve for said cylinder passage, a suction valve for said float chamber suction passage operatively associated 25 with said cylinder valve to open it when the suction valve is closed, a vent valve for said float chamber, operating connections for said float to said vent and suction valves, operating connections for said plunger to 30 said discharge valve, and a spring acting to hold said discharge valve normally closed.
7. In a device of the class described, the combination of a float chamber provided with a supply connection, a float, a cylinder 35 provided with a plunger, a discharge valve for said float chamber, a suction valve for said float chamber, a suction valve for said cylinder, a vent valve for said float chamber, operating connections for said plunger to 40 said discharge valve, a return spring for said plunger, and operating connections for said float to said suction and vent valves including a spring element operatively connected to said float and having lost motion 45 connections to said suction and vent valves whereby when the spring element is actuated by the float to a predetermined point it acts with a snap action.
8. In a device of the class described, the combination of a float chamber provided 50 with a supply connection, a float, a cylinder provided with a plunger, a rotary discharge valve for said float chamber, a suction valve for said float chamber, a suction valve for 55 said cylinder, a vent valve for said float chamber, operating connections for said plunger to said discharge valve, a return spring for said plunger, and operating connections for said float to said suction and 60 vent valves.
9. In a device of the class described, the combination of a float chamber provided with a supply connection, a float, a cylinder provided with a plunger, a discharge valve for said float chamber comprising a valve 65 for said float chamber comprising a valve
- casing and a horizontally disposed rotary disk valve mounted in said casing for limited vertical movement, a suction valve for said float chamber, a suction valve for said cylinder, a vent valve for said float chamber, operating connections for said plunger to said discharge valve, a return spring for said plunger, and operating connections for said float to said suction and vent valves. 70
10. In a device of the class described, the combination of a float chamber provided with a supply connection, a float, a suction valve for said float chamber, a vent valve for said float chamber, operating connections for said float to said suction and vent valves including a spring element operatively connected to said float and having lost motion connections to said suction and vent valves whereby when the spring element is actuated by the float to a predetermined point it 75 acts with a snap action.
11. In a device of the class described, the combination of a float chamber provided with a feed connection, a rotary discharge valve for said float chamber, a cylinder provided with a plunger operatively connected to said discharge valve, a suction control valve for said float chamber, a suction control valve for said cylinder, a vent valve for said float chamber, and operating connections for said float to said float chamber, cylinder and vent valves including a spring element whereby when the float rises or falls beyond a predetermined point the element 80 acts with a snap action to open or close the 85 valves. 90
12. In a device of the class described, the combination of a float chamber provided with a feed connection, a rotary discharge valve for said float chamber, a cylinder provided with a plunger operatively connected to said discharge valve, a suction control valve for said float chamber, a suction control valve for said cylinder, a vent valve for said float chamber, and operating connections for said float to said float chamber, cylinder and vent valves. 95
13. In a device of the class described, the combination of a float chamber provided with a feed connection, a float, a cylinder provided with a plunger, a discharge valve for said float chamber comprising a casing having a horizontally disposed rotary disk valve mounted in said casing for limited vertical movement, operating connections for said plunger to said discharge valve, a suction valve for said cylinder, and suction control means for said cylinder and float chamber including said float. 100
14. In a device of the class described, the combination of a float chamber provided with a feed connection, a float, a cylinder provided with a plunger, a rotary discharge valve for said float chamber, operating connections for said plunger to said discharge valve. 105
15. In a device of the class described, the combination of a float chamber provided with a feed connection, a float, a cylinder provided with a plunger, a discharge valve for said float chamber comprising a valve

- valve, a suction valve for said cylinder, and suction control means for said cylinder and float chamber including said float.
15. In a device of the class described, the combination of a float chamber provided with a feed connection, a discharge valve for said float chamber comprising a casing and a horizontally disposed rotary disk valve mounted in said casing for limited vertical movement, a float, and a float controlled means for actuating said valve.
16. In a device of the class described, the combination of a float chamber provided with a feed connection, a discharge valve for said float chamber comprising a casing and **15** a horizontally disposed rotary disk valve, a float, and a float controlled means for actuating said valve.
- In witness whereof I have hereunto set my hand.

FRED W. BILLIG.
